CLAIM

The ornamental design for a trailer tongue, as shown and described.

DESCRIPTION

FIG. 1 is a front, top and side perspective view of the trailer tongue embodying the design of the present invention;
FIG. 2 is a front elevational view thereof;
FIG. 3 is a rear elevational view thereof;
FIG. 4 is a right side elevational view thereof;
FIG. 5 is a left side elevatinal view thereof;
FIG. 6 is a top plan view thereof; and,
FIG. 7 is a bottom plan view thereof.

The broken away portion of the end of the trailer tongue as shown in FIGS. 1, 4, 5, 6 & 7 represents a continuation of the design uniformly along an indefinite length as is for ease and convenience of illustration.
